UNITED STATES PATENT OFFICE.

ADA O. MARTIN, OF LOS ANGELES, CALIFORNIA.

CHURN.

No. 869,189.

Specification of Letters Patent.

Patented Oct. 22, 1907.

Application filed May 11, 1907. Serial No. 373,084.

To all whom it may concern:

Be it known that I, ADA O. MARTIN, a citizen of the United States, residing at Los Angeles, in the county of Los Angeles and State of California, have 5 invented new and useful Improvements in Churns, of which the following is a specification.

This invention relates to a churn of that type provided with an oscillating barrel adapted to be actuated by a walking beam flexibly connected with the ends 10 of the barrel.

The invention has for one of its objects to improve and simplify the construction and operation of devices of this character so as to be comparatively easy and inexpensive to manufacture, extremely easy to agitate, 15 and conveniently emptied or filled.

A further object of the invention is to provide a rocking frame on which the handle or walking beam is pivoted so that the barrel will have a compound or double movement, due to the oscillation of the frame 20 and of the walking beam.

Another object of the invention is to provide flexible and elastic connections between the ends of the barrel and walking beam so as to render the barrel extremely free and sensitive in its movements.

25 With these objects in view and others, as will appear as the description proceeds, the invention comprises the various novel features of construction and arrangement of parts which will be more fully described hereinafter and set forth with particularity in the claims 30 appended hereto.

In the accompanying drawings, which illustrate one of the embodiments of the invention, Figure 1 is a side elevation of the churn. Fig. 2 is an end view thereof. Fig. 3 is a view of the cover of the barrel detached.

35 Similar reference characters are employed to designate corresponding parts throughout the several views.

Referring to the drawing, 1 designates the uprights of the frame which are provided with rockers 2 and are connected adjacent their top and bottom ends by cross 40 members 3 and 4, thus constituting an oscillating frame. Hingedly mounted at 5 on the top cross piece 4 is an operating lever or walking beam 6 formed with a hand hold 7 at its ends. Located between the uprights 1 is a barrel 8 for holding the cream to be churned and this 45 barrel is flexibly suspended on the walking beam or lever 6 by inclined helical extension springs 9. By supporting the barrel in this manner, it will receive an oscillating movement from the lever 6 about the hinge 5 as a center and also a rocking movement about the 50 rockers 2.

The barrel 8 is provided with an opening 10 in one head which is normally closed by a disk-shaped cover 11 snugly fitting the opening, which cover has a diametrical recess 12 curved outwardly at its ends and 55 adapted to receive bail-shaped locking members 13

hingedly connected at their ends to the head of the barrel, as indicated at 14. On the head is secured, by a bolt 15, an S-shaped clamping member 16 that engages over the members 13, as clearly shown in Fig. 2. In the top side of the barrel is a vent opening normally 60 closed by a stopper 17, and in the bottom is a drain opening closed by a screw cap or the like 18. At the end of the barrel opposite from that having the opening 10 and on the bottom side thereof is a ring 19 adapted to be engaged by a hook 20 on the bottom cross piece 3, 65 when it is desired to throw the barrel into the proper position for filling or emptying the same.

In practice, the barrel is moved to the dotted line position in Fig. 1 and secured by the hook 20. The cream to be churned is then placed into the barrel and 70 the cover 11 fitted in the opening 10. The members 13 are next swung inwardly to engage in the recess 12 and the clamping strip 16 turned across the member 13, thereby firmly clamping the cover in place. After detaching the hook 20 from the ring, the churn can be 75 operated by oscillating the lever 6 and simultaneously imparting a back and forth horizontal movement thereto to oscillate the entire structure on the rockers 2. By this combined movement, the barrel will be agitated 80 in a simple and thorough manner so that the churning 80 will be quickly effected. After the churning is completed, the buttermilk is first drawn off by removing the cap 18 and then the barrel is moved to the dotted line position and fastened by the hook 20 to permit the cover to be removed and the butter taken out of the 85 barrel.

A churn of the character referred to is comparatively simple and inexpensive to construct and can be made of any size suitable for toys or for domestic use.

From the foregoing description, taken in connection 90 with the accompanying drawing, the advantages of the construction and of the method of operation will be readily apparent to those skilled in the art to which the invention appertains, and while I have described the principle of operation of the invention, together with 95 the apparatus which I now consider to be the best embodiment thereof, I desire to have it understood that the apparatus shown is merely illustrative and that such changes may be made when desired, as are within the scope of the claims.

100 Having thus described the invention, what I claim is:—

1. In a churn, the combination of a rocking frame, a walking beam mounted on the frame, and a barrel flexibly suspended on the walking beam.

2. In a churn, the combination of an oscillating frame, a walking beam mounted thereon, a barrel for containing the cream to be churned, and elastic members flexibly connecting the barrel with the walking beam.

3. In a churn, the combination of a frame, rockers secured to the frame, a lever fulcrumed on the frame, a

barrel containing the cream to be churned, and springs for connecting the ends of the barrel with the lever.

4. In a churn, the combination of a rectangular vertically disposed frame, rockers on the beam thereof, a lever 5 on the top of the frame, a barrel disposed between the lever, helical extension springs connecting the ends of the barrel with the lever, and means for holding the barrel in tilted position.

5. In a churn, the combination of a frame, a walking beam thereon, a barrel disposed below the walking beam,

springs connecting the walking beam with the barrel, and means for fastening one end of the barrel to the frame to hold the former in a tilted position.

In testimony whereof, I affix my signature in presence of two witnesses.

ADA O. MARTIN.
